SAFETY HEADGEAR

Robert Dickhoff, New York, N. Y.

Application January 7, 1937, Serial No. 119,399

3 Claims.

This invention relates to new and useful improvements in a safety head gear.

The invention has for an object the construction of an article as mentioned which is capable of protecting the head of a person and adapted to be used in wars, riots, and other disturbances. More specifically, the invention contemplates characterizing the safety head gear with a steel skull cap having an opening for the face, and closing said opening with a bullet proof vision glass plate.

It is a further object of this invention to provide an arrangement which permits the glass plate to be removed and replaced in the event of breakage. Thus, more than one glass may be carried by each person.

Still further the invention proposes to provide a reinforcing bridge across the top portion of the skull cap to make it stiff, rigid and strong.

Another one of the objects of this invention is to provide layers of asbestos or other insulating material and strong lining within the skull cap to protect the head.

Another object is to arrange the head gear so that the air supply to a wearer is not hampered, and there is no cramped condition to irritate one's feelings during wearing periods.

Still further the invention also proposes an arrangement which will permit the glass plate to be lifted and maintain a slightly raised position to permit fresh air to be readily drawn into the skull cap. It is contemplated that a person may so wear the safety head gear, when there is no immediate danger.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a front elevational view of a skull cap constructed according to this invention.

Fig. 2 is a side elevational view of Fig. 1.

Fig. 3 is a fragmentary enlarged sectional view taken on the line 3—3 of Fig. 1.

Fig. 4 is a front view similar to Fig. 1 but illustrating a modification.

Fig. 5 is a fragmentary enlarged sectional view taken on the line 5—5 of Fig. 4.

The safety head gear, according to this invention, comprises a steel skull cap 10 having an opening 11 for one's face. An exchangeable bullet

proof vision glass plate 12 is provided for normally closing said opening.

The skull cap 10 is formed with a reinforcing bridge 13 extending across the top thereof from slightly above the brow to the back of the head. Within the skull cap at the back of the head there are several layers of material 14. These layers preferably comprise layers of asbestos and strong lining material and are for the purpose of protecting one's head from excessive heat when it is required of the wearer to pass through hot zones and fire zones.

A leather strap 15 is attached along the bottom edge of the skull cap at the sides and the back and has strap portions 15a adapted to engage beneath the wearer's neck. A buckle 16 is associated with the strap portions 15a holding the strap portions together in various adjusted positions and so provide for attaching the head gear upon different persons. Air may enter the head gear at the front near the chin of a wearer.

Along the edge of the opening 11 there is a U-shaped track element 18. This track element has an open top side. The glass plate 12 is slid in from the top. It is maintained in position by several pin bolts 19. Each of the pin bolts 19 comprises a screw or bolt portion 19a which is mounted upon the material of the skull cap and which supports a washer portion 19b engaging over the top edge of the glass plate. When desired, the washer portion 19b may be pivoted to the position indicated by the dot and dash lines in Fig. 3 and this will take the pressure off the bolt portion 19a which then may be removed to permit removal of the glass plate. The track 18 is provided with a soft protective pad 18a which engages against the edges of the glass plate 12 to protect the edges from undue shock and breakage.

In Figs. 4 and 5 a modified form of the invention has been disclosed which distinguishes from the prior form in several respects. According to this form there are adjustable pin bolts 29 adapted to hold the glass plate 12 downwards, completely within the track as indicated by the dot and dash lines 12a, or in a raised position. A spring 30 is mounted on the bottom portion of the track and normally urges the glass plate 12 into the raised position.

Each pin bolt 29 comprises a wing head clamp screw 31 upon which a cam element 32 is mounted. This cam element engages against the edge of the plate 12. When the cam element is in the position shown by the full lines on the drawing the glass plate 12 will be raised by the spring 30. Then there is a small opening 33 between the

bottom edge of the glass plate and the opening 11 in the skull cap through which air may be readily drawn and through which the user may easily converse. When an emergency arises it 5 is merely necessary for the wearer to loosen the wing screws 31, turn the cams 32 into downward extending positions, and then turn in the wing screws to hold the cams in these positions.

While I have illustrated and described the preferred embodiments of my invention, it is to be understood that I do not limit myself to the precise constructions herein disclosed and the right is reserved to all changes and modifications coming within the scope of the invention as 15 defined in the appended claims.

Having thus described my invention, what I claim as new, and desire to secure by United States Letters Patent is:—

1. A safety head gear comprising a steel skull 20 cap having an opening for the face, a U-shaped track extended along the sides and the bottom of said opening, an exchangeable bullet proof vision glass plate mounted on said track for closing said opening, and said pin bolts for holding 25 said glass plate upon said track, each pin bolt having a wing screw portion supporting a cam portion which may be turned upwards or downwards, and resilient means urging said glass plate upwards against the cam portion.

30 2. A safety head gear comprising a steel skull

cap having an opening for the face, a U-shaped track extended along the sides and the bottom of said opening, an exchangeable bullet proof vision glass plate mounted on said track for closing said opening, and said pin bolts for holding 5 said glass plate upon said track, each pin bolt having a wing screw portion supporting a cam portion which may be turned upwards or downwards, and resilient means urging said glass plate upwards against the cam portion, said resilient 10 means comprising a spring mounted upon said track and engaging the edge of said glass plate.

3. A safety head gear, comprising a steel skull cap having an opening for the face, a U-shaped track extended along the sides and the bottom of 15 said opening, an exchangeable bullet proof glass plate mounted on said track for closing said opening, elements mounted along the open side of said track and being adapted to engage the top edge of said glass plate for releasably holding 20 said glass plate in position on said track, and resilient means mounted on the lower portion of said track and operating between said track and the lower edge of said glass plate to force 25 said glass plate against said elements in the released position thereof to form a slight opening at the bottom edge of said glass plate through which air may enter said cap.

ROBERT DICKHOFF. 30
